US0D1061473S

(12) **United States Design Patent** (10) **Patent No.:** **US D1,061,473 S**
(45) **Date of Patent:** **** Feb. 11, 2025**

(54) **HEADSET**

(71) Applicant: **Sonusmed, Incorporated**, Gilbert, AZ (US)

(72) Inventors: **Anju Dubey**, Gilbert, AZ (US); **Shreya Dubey**, Gilbert, AZ (US)

(73) Assignee: **Sonusmed Incorporated**, Gilbert, AZ (US)

(**) Term: **15 Years**

(21) Appl. No.: **29/878,735**

(22) Filed: **Jun. 27, 2023**

Related U.S. Application Data

(63) Continuation of application No. 16/695,389, filed on Nov. 26, 2019, now abandoned, which is a continuation-in-part of application No. 15/480,179, filed on Apr. 5, 2017, now abandoned.

CLAIM

The ornamental design for a headset, as shown and described.

DESCRIPTION

FIG. 1 is a top isometric view of a headset showing our new design; and,

FIG. 2 is a side view of the headset of FIG. 1.

The dash-dash broken lines represent unclaimed environmental structure and form no part of the claimed design.

1 Claim, 2 Drawing Sheets
